[57] CLAIM

The ornamental design for a caster plate for coupling a wheelchair caster fork to a wheelchair caster leg, as shown and described.

DESCRIPTION

FIG. 1 is a rear perspective view of a caster plate for coupling a wheelchair caster fork to a wheelchair caster leg showing my new design;

FIG. 2 is a front view thereof with the rear being a mirror image thereof;

FIG. 3 is a right side view thereof;

FIG. 4 is a left side view thereof;

FIG. 5 is a top plan view thereof; and,

FIG. 6 is an exploded perspective view thereof.

The broken line in FIG. 1 showing the wheelchair frame, caster leg, caster fork, and caster is for illustrative purposes only and forms no part of the claimed design.
